CLAIM

The ornamental design for a whiskey barrel shaped pickup truck cap, as shown and described.

DESCRIPTION

FIG. 1 is a top side, right side, rear side perspective view of a first embodiment of the present invention, the enlarged detail for FIG. 1 showing that the hex shaped heads visible on the barrel bands are not part of the first embodiment. Note the size of the hex shaped heads in the views outside of the enlarged detail section do not allow for discernable dashed lines but should be considered to be drawn in dashed lines; FIG. 2 is a top plan view of the claimed design of FIG. 1, the bottom plan view is omitted from this embodiment as the bottom view is not claimed within this embodiment; FIG. 3 is a rear side elevation of the claimed design of FIG. 1, wherein the size and shape of any rear opening into the interior of the whisky barrel shaped pickup truck cap is not part of the claimed invention; FIG. 4 is a front side elevation of the claimed design of FIG. 1; FIG. 5 is a right side elevation of the claimed design of FIG. 1; and, FIG. 6 is a left side elevation of the claimed design of FIG. 1. The broken lines in the drawings illustrate environmental subject matter that forms no part of the claimed design.
